UNITED STATES PATENT OFFICE.

RALPH L. STORM, OF WATERLOO, IOWA, ASSIGNOR TO STORM RAILWAY SIGNAL COMPANY, OF WATERLOO, IOWA.

AUTOMATIC SIGNAL FOR ELECTRIC RAILWAYS.

SPECIFICATION forming part of Letters Patent No. 701,275, dated May 27, 1902.

Application filed July 25, 1901. Serial No. 69,670. (No model.)

To all whom it may concern:

Be it known that I, RALPH L. STORM, a citizen of the United States of America, and a resident of the city of Waterloo, Blackhawk county, Iowa, have invented certain new and useful Improvements in Automatic Signals for Electric Railways, of which the following is a specification.

My invention relates to improvements in automatic signals for electric railways; and the object of my improvement is to provide a switch having drop-blocks adapted to automatically break circuit through the action of gravity and having an improved step-by-step signaling device, the whole operative by the impact on the gravity drop-blocks of swing-blocks operated by the trolley-wheel of a passing car. I attain this object by the means illustrated in the accompanying drawings, in which—

Figure 1 is a side elevation of my combined gravity drop-switch and step-by-step circuit-closer. Fig. 2 is a plan view of the same. Fig. 3 is a detail view showing the method of bringing the hooks into contact with the conducting-surfaces of the gravity drop-blocks. Fig. 4 is a perspective view of the releasing ratchet-wheel. Fig. 5 is a perspective view of the setting ratchet-wheel, both being parts of the circuit-closer; and Fig. 6 is a diagram of the wiring.

Similar numbers refer to similar parts throughout the several views.

Attached to suitable supports on the frame 35 50 are two electromagnets 25 and 26, which as herein shown are solenoids, having their cores 45 and 46 movable vertically within them. To the lower ends of the said cores are pivoted the pawls 27 and 28, which respectively engage the teeth of the ratchets 29 and 30. The ratchet-wheels 29 and 30 are separately mounted and are each revolvable about the bolt 35. The flat springs 36 and 37 are arranged to bear, respectively, against the lower teeth of said ratchet-wheels 29 and 30 in order to keep said ratchets normally in contact with the pawls 27 and 28. The ratchet-wheel 30, its hub 87 and stud 89, also the ratchet-wheel 29, its hub 88 and stud 90, 45 50 are constructed of any suitable non-conducting material. The circumferential periphery

of the hub 87 is covered with a conducting-ring 32, having a projecting tongue-piece 34. The circumferential periphery of the hub 88 is partially surrounded by the conducting-ring 31, a piece of the latter being removed in order to expose the non-conducting surface of the hub 88. A connecting-plate 91 is extended inwardly from the conducting-ring 31 along the inner face of the hub 88 and is perforated to admit of the passage through it and contact with the bolt 35. When in position and ready for operation the inner faces of the hubs 87 and 88 are set parallel to each other, but not in contact. The studs 89 and 90 then engage each other, keeping the ratchets 29 and 30 locked in line, at which time the projecting tongue 34 is over the part of the hub 88 where part of the conducting-ring 31 has been removed. A collar on the bolt 35 serves to keep the hubs 87 and 88 apart.

When not in operation, there is no electrical communication between the conducting-rings 31 and 32, for the projecting tongue 34 then lies directly over the break in the ring 31 and out of contact with it. Communication between the two is established when the setting-pawl 28 rotates the setting-ratchet 30 over a space of one tooth and brings the projecting tongue 34 into contact with the conducting-ring 31, as is indicated by the dotted lines in Fig. 2. The electrical current is brought direct from the trolley-wire through the medium of the wire 83 and the spring 38, 85 the latter having its free end bearing against the under surface of the conducting-ring 32. A wire 66 serves to connect the bolt 35 with the upper lamp 59.

66 is a wire which serves to ground the current passing through the electromagnets 25 and 26 by means of the ground-wire 70.

48 and 49 are drop-blocks arranged to move vertically within openings in the frame 50, having their lower ends normally a short distance above the trolley-wire 71. These drop-blocks are formed of non-conducting material, but have conducting-plates 39 and 40, respectively, attached to their upper surfaces.

41 and 42 are terminal plates insulated from each other and supported by a projection 44 on the frame 50. The plate 41 bears against

the conducting-plate 40 when the drop 49 is vertically raised, and the plate 42 bears against the conducting-plate 39 when the drop 48 is vertically raised. An electrical current is carried to the electromagnet 25 from the terminal 41 by means of the wire 85. An electrical current is carried to the electromagnet 26 from the terminal 42 by means of the wire 84. A framework 51 is placed over the gravity-drops 48 and 49 and is slotted to permit the upper parts of the drops to pass through and come in contact with the conducting-strip 52. The conducting-strip 52 is fastened at an intermediate point to the framework 51, and its free ends are movable vertically to allow them to come into contact with the conducting-hooks 53 and 54, respectively, when either of the drops 48 or 49 is pressed up against them. The conducting-hooks 53 and 54 carry the current from the trolley-wire by means of the intermediate conducting-strip 55. A swing-block 56 is suspended from the frame 50 between the lower ends of the gravity drop-blocks 48 and 49. The block 56 is slotted to permit it to ride astride of the trolley-wire 71. The signal-lamps 59 and 57, 60 and 58, which are located near the ends of the track-sections, are arranged, as shown, with a single lamp above a group of lamps. The lamps are adapted to be lighted alternately. The block 56 is, when impinged upon by the trolley-wheel 80 of a car 81, just entering a section of track 82, pressed up against the gravity-drop 48, lifting the latter into a position where its conducting-surface 39 comes into contact with the conducting-strip 52 and brings the latter into contact with the hook 53. The current is carried from the trolley-wire 71, through the strip 55, hook 53, strip 52, plates 39 and 42, and the wire 84, to the setting-electromagnet 26, which moves the core 46 vertically upward, carrying with it the setting-pawl 28, which moves the setting ratchet-wheel forward through the space of one tooth. This rotation of the setting ratchet-wheel carries forward the projecting piece 34 beyond the neutral place and bringing it into contact with the conducting-ring 31. A circuit is then established from the trolley-wire 71 through the lamp 59 by means of the wire 83, spring 88, conducting-ring 32, tongue-piece 34, conducting-ring 31, plate 91, bolt 35, and wire 66. After passing through and lighting the lamp 59 the circuit is established through the wires 67, 62, and 79 to the lamps 58, which are lighted, thence to the ground through the wire 78.

When any car on a section is about to move to another section, its trolley-wheel impinges upon the block 56, lifting the drop 49', and bringing the plate 40 into contact with the strip 52. A current from the trolley-wire 71 then passes through the strip 55', hook 54', strip 52, plates 40 and 41, and wire 85' to the releasing-magnet 25'. Its core being lifted causes the pawl to move the releasing ratchet-wheel forward through the space of one tooth.

In case this car is the only one on the track-section the neutral space on the hub of the releasing-ratchet is then carried forward under the tongue-piece 34, and the circuit being broken the lamps 59 and 58 are extinguished, indicating a clear track. If one or more cars yet remain on the section after this first car has passed off, inasmuch as the setting ratchet-wheel has moved forward as many teeth as there are cars which have passed upon the section, the rotation of the releasing ratchet-wheel does not cause a break in the circuit until the last car has passed off the section and the tongue 34 rests over the neutral space aforesaid. The releasing ratchet-wheel at the opposite end of the section is similarly operated by a current which is derived from the trolley-wire 71 and passes over the wires 85, 72, 61, and 65 to the conducting-plate on the drop 49, thence to the releasing mechanism.

When a car enters the track-section 82 from the opposite end to that described, it causes the lighting of the lamps 60 and 57 by means of a current passing through the wires 67', 75, 63, and 68 and from the lamps 57 to the ground.

The claims below are intended to cover the construction of the gravity-drop herein shown and described when used in connection with a circuit-closer such as shown and described herein or of any construction covered by the terms of the claims themselves.

No claim is made to the circuit-closer in this application nor in a companion application filed July 25, 1901, and bearing Serial No. 69,671, such circuit-closer being described and claimed in an application filed by Charles H. Storm, June 19, 1901, and bearing Serial No. 43,857, and which invention is now owned by me.

What I claim as constituting the present invention is—

1. The combination with a frame supported above a trolley-wire and having openings, drop-blocks movable within said openings operated by gravity and faced on their upper ends with conducting-plates, terminals adapted to make independent contact with said plates when the blocks are raised, a strip adapted to make contact with either plate when its block is raised, and circuits leading from said strip through a source of power and electromagnets to said terminals; of a swing-block supported by the frame between said drop-blocks and slotted so as to stand astride the trolley-wire, the swing-block being adapted when swung mechanically in either direction by a passing trolley-wheel to raise one of said drop-blocks and close the circuit, as and for the purpose set forth.

2. The combination with a frame supported above a trolley-wire and having openings, drop-blocks movable within said openings operated by gravity and faced on their upper ends with conducting-plates, terminals adapted to make independent contact with said plates when the blocks are raised, a strip

adapted to make contact with either plate when its block is raised, a main circuit including a source of power and the work to be performed, devices for making and breaking said main circuit, and a second circuit leading through said devices and a source of power to said terminals and plate; of means for permitting the trolley-wheel to pass beneath the first and to raise the second of said blocks 10 mechanically when the car is passing in either direction, as and for the purpose set forth.

3. The combination with a frame supported above a trolley-wire and having openings, drop-blocks movable within said openings operated by gravity and faced on their upper ends with conducting-plates, terminals adapted to make independent contact with said plates when the blocks are raised, a strip adapted to make contact with either plate 20 when its block is raised, a main circuit including a source of power and the work to be performed, devices for making and breaking said main circuit, and a second circuit leading through said devices and a source of power 25 to said terminals and plate; of a swing-block suspended from the frame between the drop-blocks and adapted when swung in either direction by a passing trolley-wheel to raise one block mechanically and establish the second 30 circuit above mentioned, as and for the purpose set forth.

4. The combination with two vertically movable drop-blocks operated by gravity and faced on their upper ends with conducting- 35 plates, a supporting-frame having a projection between said blocks, terminals mounted on the projection and adapted to contact with either plate when its block is raised, and means for permitting a trolley-wheel to pass under 40 the first of said blocks in either direction and to mechanically raise the second; of a slotted framework standing above the blocks, a strip centrally attached to said framework with its

extremities adapted to contact with either plate when its block is raised, and circuits 45 leading from said strip through a source of power and the work to be performed and to said terminals, as and for the purpose set forth.

5. The combination with two vertically movable drop-blocks operated by gravity and faced on their upper ends with conducting- 50 plates, a supporting-frame having a projection between said blocks, terminals mounted on the projection and adapted to contact with either plate when its block is raised, and means 55 for permitting a trolley-wheel to pass under the first of said blocks in either direction and to mechanically raise the second; of a slotted framework standing above the blocks, a strip centrally attached to said framework with its 60 extremities adapted to contact with either plate when its block is raised, hooks standing above said extremities of the strip, and circuits leading through said hooks, a source of power, and the work to be performed, as and 65 for the purpose set forth.

6. In an automatic signal for electric railways, the combination with drop-blocks movable vertically by impact upon them, of a trolley-wheel passing in either direction, and circuits including a source of power and two electromagnets through one of which an impulse is passed when a block is raised; of a second circuit including a pair of signals at opposite ends of the track-section, and devices 75 for making and breaking this circuit which devices include two ratchet-wheels intermittently rotated when said magnets are alternately energized, all as and for the purpose set forth. 80

Signed by me at Waterloo, Iowa, this 20th day of July, 1901.

RALPH L. STORM.
